(57) **CLAIM**

The ornamental design for an orthodontic elastomeric ligature tie, as shown and described.

DESCRIPTION

FIG. 1 is a front perspective view of an orthodontic elastomeric ligature tie, showing my new design;

FIG. 2 is a front elevational view thereof;

FIG. 3 is a back elevational view thereof;

FIG. 4 is a side elevational view thereof, and the opposite side elevational view is a mirror image of the side elevational view thereof;

FIG. 5 is a top elevational view thereof, and the opposite bottom elevational view is a mirror image of the top elevational view thereof; and,

FIG. 6 is a front perspective view thereof, wherein the broken line showing of a heart is for the purpose of illustrating an environment and forms no part of the claimed design.
